United States Patent Office

Des. 205,799
Patented Sept. 20, 1966

205,799

STACKING BOX OR THE LIKE

Roy C. Josephsen, 230 Oak Ridge Road, Hillsdale, N.J.,
and Clifford L. Weir, 62 Rolling Hills Drive, Wayne, N.J.

Filed Oct. 11, 1965, Ser. No. 87,418

Term of patent 14 years

(Cl. D58—12.6)

We claim:

The ornamental design for a stacking box or the like, as shown and described.
